CHARLES F. STODDARD, OF NEW YORK, N. Y.

AUTOMATIC MUSICAL INSTRUMENT.

1,282,137.

Specification of Letters Patent. Patented Oct. 22, 1918.

Application filed March 23, 1910, Serial No. 551,061. Renewed February 26, 1918. Serial No. 219,726.

To all whom it may concern:

Be it known that I, CHARLES F. STODDARD, a citizen of the United States, residing at New York, in the county of New York and State of New York, have invented an Improvement in Automatic Musical Instruments, of which the following description, in connection with the accompanying drawings, is a specification, like letters on the drawings representing like parts.

This invention relates to mechanism for playing musical instruments such as pianos; and pertains more particularly to means for governing and varying tone intensities.

Among other objects, the invention is intended to provide an apparatus capable of governing the energy used for sounding a tone or tones, as for striking the strings of a piano; and the invention contemplates simple and stable, though accurate and effective means to this end.

For illustration, the accompanying drawing shows one practicable embodiment of the invention employing suitable pneumatically governed devices in co-operation with a piano action. This illustrative embodiment comprises apparatus whereby a musical composition may be played and the expression thereof regulated and varied, with a variety of degrees of emphasis or repression, by wholly automatic means independently, if preferred, of any human direction or control; and comprises, also, means whereby such completely automatic expression control may be modified at will, while preserving in general, the characteristics of expression intended to be produced by automatic apparatus; and comprises also apparatus whereby the effect of automatic expression control can be predetermined, at the will of the operator, to play with any one of a number of available intensities. Said illustrative embodiment comprises other features of importance which will be pointed out in the discussion which is to follow:

The character of the invention may be best understood by reference to the accompanying drawings, in which the specific illustrative embodiment above referred to is shown diagrammatically.

In the drawings:

Figure 1 is a diagrammatic representation of a typical piano action with operating and governing means embodying the invention;

Fig. 2 is a sectional view of one of the parts shown in Fig. 1 as hereinafter explained.

Fig. 3 is a fragmentary view of one type of note sheet which may be used in the apparatus of Fig. 1; and

Fig. 4 is a fragmentary view of another type of note sheet which may be used in the apparatus of Fig. 1.

Referring to the drawings, a typical piano action is shown in its normal position of rest. The illustrative action comprises a key-controlled sticker B, to act on a wippen I. The hammer C, damper E, string D and other parts of the action may be those well-known in the art. To operate the action pneumatically a motor pneumatic F is provided, having a sticker H to act upon the wippen I. A wind truck 7 leads to the wind chest of the motor pneumatics, each of which has a secondary valve 8, controlled by a primary valve 9 operated from the tracker board G through a duct 10 in the usual manner.

The trunk 7 communicates with a regulated pressure chest 12. A high exhaust chest 14 arranged for communication with the chest 12, may be connected by a trunk 15 with any source of exhaust such as feeder bellows of any practicable type.

Between the high exhaust chest 14 and the regulated pressure chest 12 is a chamber 30, open at its lower extremity to the chest 14 and communicating with the chest 12 through suitable ports. The chamber contains a piston valve 31, which governs communication between the two chests so as to subject the regulated pressure more or less to the influence of the high exhaust.

The stem 32 of the valve 31 projects upwardly through the top of the chamber 30, into a cylinder of graduated diameter. Within the cylinder, in the illustrative embodiment shown, is a unitary piston of graduated diameter corresponding in shape to the interior of the cylinder. Said piston comprises the three superposed cylindrical parts 34, 35 and 36, presenting respectively the acting areas x, y and z.

Also connected to the stem 32 of the piston structure is a tension spring 37 which has its end connected to a key 38 by which the tension of the spring may be adjusted. The spring is preferably so adjusted as to exert continuously an upward pull upon the piston structure. This upward pull may be

varied when necessary by means of the key 38; but this capacity for adjustment may be neglected for the present and the upward pull by the spring may be considered substantially constant disregarding the minute fluctuations in tension of the spring resulting from negligible elongation and contraction accompanying movement of the piston structure. This substantially uniform pull of the spring contributes to control the piston structure and valve 31 as presently described.

In discussing the various pneumatic influences brought to bear upon the piston structure, the so-called "exhaust" or "air tension" will be treated as having a positive pressure relative to a perfect vacuum of zero pressure. This mode of treatment is more convenient in explaining the operation of the piston structure than would be the case if exhaust were considered in the popular sense of exerting a pull by suction as distinguished from a push by pressure.

Ducts 40, 41 and 42 enter respectively the cylinder chambers opposite the piston faces x , y and z . Each duct is controlled (as hereinafter explained) so as to admit to its cylinder chamber either atmospheric pressure, or regulated pressure from the chest 12; and the regulated pressure may be admitted to any one or more, or all, of the chambers while atmospheric pressure will be present in those chambers, if any, which do not contain regulated pressure. These pressures within the cylinder chambers act upwardly upon the piston faces x , y and z , and together with the upward pull of the spring 37, constitute the forces tending to move the piston structure upwardly.

These upwardly directed forces are opposed by atmospheric pressure acting downwardly upon the interior of the piston structure, which is open to atmosphere through a port 43. In the illustrative apparatus the upwardly exposed piston areas substantially equal the downwardly exposed areas x , y and z . If, therefore, atmosphere be admitted to all the cylinder chambers, its upward pressure on the areas x , y and z will be opposed and balanced by equal downward pressure of atmosphere upon equal areas. This leaves the spring 37 unopposed except by gravity to lift the piston valve 31 and open the valve ports to the fullest extent, thereby subjecting regulated pressure in the chest 12 to the maximum influence of high exhaust in the chest 14. Under these conditions notes are sounded with maximum loudness.

When the present invention is embodied in a construction which employs exhaust as distinguished from compressed air, the regulated exhaust or pressure is always less than atmospheric pressure. Consequently when regulated pressure is admitted to all the cyl-

inder chambers, the upward pneumatic pressure on the piston structure is then at its minimum, being, of course, less than when atmosphere is admitted to any one or more of the cylinder chambers. Downward atmospheric pressure, being thus opposed by the minimum pneumatic upward pressure, substantially predominates and moves the piston structure downwardly, the spring 37 preferably having its tension adjusted so that its upward pull will be overcome more or less by said downward atmospheric pressure. This downward movement of the piston structure tends to close the valve ports between the chests 12 and 14 with the result that regulated pressure may be largely cut off from the influence of high exhaust in the chest 14. Under these conditions, i. e. when regulated pressure is admitted to all the cylinder chambers, notes are played with minimum loudness available in the specific apparatus illustrated in the drawings.

It will be evident to those skilled in the art, that the greater the piston area exposed to regulated pressure, the greater will be the predominance of downwardly acting atmospheric pressure and the greater will be the constriction of communication between the chests 12 and 14. In other words, the greater the piston area exposed to regulated pressure, the less is regulated pressure subjected to the influence of high exhaust and the less will be the intensity of sounded notes. Accordingly, the general operation of the cylinder and piston structure described above may be conveniently summarized thus:—admitting regulated pressure to a cylinder chamber diminishes intensity; admitting atmospheric pressure to a cylinder chamber increases intensity.

There is always some leakage of atmosphere to the chest 12 as, for instance, past the various valve mechanisms and from the motor pneumatics, such leakage tending constantly to increase regulated pressure and actually increasing it unless the leakage be fully compensated by exhaust through the chest 14 by way of the valve ports in the chamber 30. Under these circumstances, whenever the piston structure moves downwardly and thereby restricts the openings between the chests 12 and 14 the result is to increase regulated pressure. This increase is regulated pressure is, of course, communicated practically instantaneously to those cylinder chambers which contain regulated pressure. Consequently, whenever the piston structure moves downwardly because of downward atmospheric pressure predominating over upward regulated pressure, the indirect result is to increase the upwardly acting regulated pressure and thereby to decrease the predominance of downward atmospheric pressure. The greater the extent of downward movement of the piston struc-

ture—the greater will be the described decrease in the predominance of downward atmospheric pressure.

In any instance the piston structure will move downwardly until the predominance of downward atmospheric pressure diminishes to such an extent that the upward pull of the spring balances the diminished predominance of downward atmospheric pressure, whereupon the piston structure comes to rest.

In like manner, whenever the piston structure moves upwardly to enlarge the openings between the chests 12 and 14, the effect is to diminish regulated pressure by exhaust through the chest 14. This diminution in regulated pressure is communicated to those cylinder chambers which contain regulated pressure; and consequently the upward regulated pressure on the piston is diminished. In other words the piston structure moves upwardly because of the predominance of upward pneumatic pressure plus the pull of the spring; such upward movement of the piston structure has the effect of decreasing the predominance of upward pressure and such decrease continues during upward movement of the piston structure until there is no longer any predominance and the opposed forces are balanced, whereupon the piston structure comes to rest.

In the operation of the specific illustrative apparatus, therefore, the piston structure is constantly under the control of opposed forces tending always to balance each other and hold the piston structure, as it were, in suspension between them; that is to say, the specific apparatus tends constantly to establish a balancing equation between the opposed forces acting upon the piston. Such movement of the piston structure as may occur when that balancing equation is disturbed, takes place practically instantaneously so that a new balancing equation appropriate to the newly-initiated conditions is immediately set up.

The actual variation of regulated pressure may result from a number of causes, or a combination of causes, such that the piston structure and valve 31 may or may not be moved to assist in a reestablishment of the pressure equation above referred to, which holds the piston structure at rest and in balance.

Normally, and even at a time when it is desired to maintain constant regulated pressure, some leakage of atmosphere to the chest 12, and various parts communicating therewith, may tend to reduce the regulated tension in said chest, whether or not any of the motor pneumatics F is in action. A reduction in regulated tension from such cause may be compensated to some extent by leakage between the high tension chest 14 and the chest 12, as by leakage past the piston

valve 31. If, however, regulated pressure increases enough to disturb a prevailing pressure equation, there may result an upward movement of the piston structure, enlarging the openings between the chests 12 and 14 enough to permit high exhaust to restore the intended regulated pressure in chest 12. Such action takes place so promptly and quickly, that in effect, it serves to maintain regulated tension substantially constant (until intentionally adjusted) rather than to restore it.

Each motor pneumatic F , when idle, contains atmosphere which tends to increase regulated pressure in the chest 12, when the pneumatic is thrown into operation. Obviously, if several motor pneumatics F act simultaneously there may be a considerable increase of regulated pressure. Ordinarily, in the operation of the illustrative apparatus, the regulated pressure may be thus subjected to frequent fluctuations by the action of the motor pneumatics. Whenever such fluctuation so increases regulated pressure that a pressure equation is disturbed, the piston valve 31 may be moved to restore the equation described. As already suggested, this restoring action takes place so quickly that it is rather a maintaining action in respect to its general effect upon the regulated pressure.

From the above it appears that whatever drafts are made upon the regulated pressure chest 12, and from whatever cause, said pressure may be maintained always by the described balancing operation of the piston structure controlling communication between the chests 12 and 14. Immediately, however, when a deliberate, intentional change is made in the piston area exposed to regulated pressure, the pressure equation is temporarily disturbed, to be restored when a new and different regulated pressure is established.

It will be noted that the regulating action of the piston structure may serve merely to maintain the desired regulated pressure in spite of any drafts made thereupon, as for instance, by the motor pneumatics. That is to say, the regulation does not necessarily result from varying communication between the high exhaust chest and the regulated pressure chest. For instance, assume that the piston area acted upon by the regulated pressure be so changed that a considerable increase in regulated pressure is demanded to reestablish the pressure equation. Assume further that this change in piston area be accompanied by the action of a considerable number of motor pneumatics F , which in effect alone suffices to increase the regulated pressure so as to reestablish the balancing pressure equation. Under such circumstances regulated pressure is changed from a lower to a higher working level.

without making necessary any change in the communication between the two chests 12 and 14. Thus in greater or less degree, the mere utilization of regulated pressure in 5 the chest 12, may coöperate with the deliberate variations of piston area acted upon by the regulated pressure, so that the control of communication between the chests 10 exercised by the piston valve may be, and frequently it will be, of supplemental and auxiliary effect.

The preceding description pertains to an illustrative form of expression-controlling means by which changes in pneumatic condition affecting the operation of the motor pneumatics is more or less immediately varied and controlled. The manner in which such expression-controlling means or its equivalent or substitute, may be governed to 15 cause notes to be played with different intensities, will be next explained.

The specific illustrative apparatus of the drawings comprises mechanism whereby the immediate expression-controlling means 20 may be governed wholly automatically, as, for instance, by the ultimate control of supplementary perforations in a note sheet or the like. This wholly automatic control of the immediate expression means will be first 25 described.

Referring again to the drawings, the duct 40 leads to a so-called "three-way" valve or switch 46 (shown also in Fig. 2) by which the duct 40 may be thrown into communication 30 with the wholly automatic governing mechanism and alternatively with an illustrative, partly manual control hereinafter more fully described. In the position illustrated in Figs. 1 and 2, the valve 46 is in 35 position to cause the duct 40 to communicate with the partly manual control mechanism referred to; but for the present it will be assumed that the valve or switch 46 is turned to open communication between 40 the duct 40 and a duct 40^a leading to the 45 illustrative wholly automatic governing mechanism about to be described.

It is preferred that the switch 46 affect, in its respective positions, a number of different ducts in addition to the duct 40. To 50 suit this purpose the valve 46 may comprise a cylindrical plug as shown in Fig. 2, fitting snugly in a casing 47 and having milled therein a number of segmental or 55 like recesses 48. As shown in Fig. 1 the valve 46 may be provided with a handle enabling it to be turned manually or otherwise. When the valve is turned through ninety degrees from the position shown in 60 Fig. 2, it will throw the duct 40 into communication with the duct 40^a as already suggested. For the present, therefore, we may consider the duct 40^a, as, in effect, a continuation of the duct 40.

65 Thus the ducts 40 and 40^a connect the

cylinder chamber opposite the piston area α with a valve chamber 49. In said chamber is a duplex valve 50 arranged for opening an upper port to atmosphere and alternatively opening a port from the chamber 49 through a duct 51 to the regulated pressure chest 12. The valve 50 is controlled by a diaphragm over a chamber 54 which communicates with a duct 56. A duplex valve 58 controls a port from the duct 56 to 70 atmosphere, and a second port from the duct 56 to a chamber 59 communicating by a duct 60 with the high exhaust chest 14. The valve 58 is controlled by a dia- 75 phragm over a chamber 62 into which leads 80 a duct 63 which passes to the casing 47 of the valve 46. When the valve 46 is in position to open the duct 40 to the duct 40^a, it also opens the duct 63 to a duct 63^a leading to a tracker vent T.

When the tracker T is open atmosphere is admitted through ducts 63^a and 63 to the chamber 62, the diaphragm of which is thereby distended and the valve 58 elevated so as to vent the diaphragm chamber 54 to 90 atmosphere and distend its diaphragm to elevate the valve 50 and vent the ducts 40^a and 40 to atmosphere, thereby admitting atmosphere to the cylinder of the piston structure opposite the piston face α . The con- 95 verse of this operation, whereby the ducts 40 and 40^a are closed to atmosphere and opened to regulated pressure, will be described hereinafter.

The duct 41 from the cylinder of the expression-controlling means leads also to the valve 46 and communicates with the duct 41^a when the valve is set to open communication between the ducts 40 and 40^a, in the manner already described.

The valve mechanism already described, whereby atmosphere may be admitted to the ducts 40^a and 40, is duplicated to control the admission of atmosphere to the ducts 41^a and 41, the corresponding parts of the valve 100 mechanism for the latter being indicated by the numerals 149, 151, 152, etc.—i. e. each part being numbered like the corresponding part of the valve mechanism for the duct 40^a, with the addition of a hundred digit 1. 115

In the valve mechanism for the duct 41^a, a duct 163 leads to the valve or switch 46 which, in the assumed position of said valve, holds the duct 163 in communication with the duct 163^a leading to a tracker vent T^a. 120 As the valve mechanism for the duct 41^a is shown in Fig. 1, it is assumed that the tracker vent T^a is open, admitting atmosphere to the ducts 163^a and 163, thereby distending the diaphragm of chamber 162, venting duct 156 and chamber 154 to atmosphere and admitting atmosphere to the ducts 41^a and 41 and to the cylinder chamber opposite the piston face γ . Thus, whenever a tracker vent T or T^a is open, atmos- 125 130

phere is admitted to the corresponding cylinder chamber. When the valve 46 is in the position assumed for the present, it opens communication between the ducts 40 and 40^a, 41 and 41^a, 63 and 63^a, and 163 and 163^a.

For the purpose of the specific apparatus of the drawing, it is unnecessary to connect the duct 42 with the switch 46. Accordingly 10 the duct 42 may lead directly to a valve chamber 249 which may be exactly like the chambers 149 and 49 for the other two valve mechanisms, which control respectively the ducts 41^a and 40^a. Associated with the 15 chamber 249 are a duplex valve 250; duct 251, diaphragm chamber 254; and other parts corresponding to those already described in connection with the ducts 41^a and the duct 40^a, such parts pertaining to the 20 duct 42 being indicated by like reference characters having the hundred digit 2. A duct 263 leading to the diaphragm chamber 262 may pass directly to a tracker vent T^b as shown in Fig. 1. As in the case of the 25 other tracker controlled valve mechanisms, the admission of atmosphere at the tracker vent T^b distends the diaphragm of chamber 262, lifts the valve 258, vents the diaphragm chamber 254 to atmosphere, lifts the valve 250, and admits atmosphere to the chamber 249, duct 42 and to the cylinder chamber opposite the piston face z.

When one of the valves 50, 150 or 250 is once opened by venting the corresponding 30 tracker duct, the valve preferably continues open even though the tracker vent may be immediately closed, as, for instance, when the tracker vent is opened by a circular perforation in a traveling music sheet. In the 35 specific apparatus, this result arises from the fact that once the valve 158, for example, is opened to admit atmosphere to the diaphragm chamber 154, said valve 158 is held in that position by atmosphere admitted 40 past the valve 158 into a duct 170 through a bleeder vent 172, and duct 174 (shown in dotted lines), which communicates with the diaphragm chamber 162. The chamber 159 above the diaphragm communicates as described with the high exhaust chest 14. Thus so long as atmosphere is admitted 45 through duct 170 to duct 174, the diaphragm of chamber 162 will remain distended and atmosphere will continue in the corresponding cylinder chamber y. The parts just described as pertaining to the valve 150 are duplicated to correspond with the valves 50 and 250.

From the preceding discussion it will appear that small perforations, circular for instance, in a music sheet may be employed to open the tracker vents T, T^a and T^b which may be immediately closed thereafter if desired. When used with the illustrative apparatus, each such perforation has the ef-

fect of introducing atmosphere to a cylinder chamber, and even after the tracker vent is closed, atmosphere will continue in the cylinder chamber until purposely exhausted at any desired subsequent time in a manner such as that about to be described.

The specific apparatus shown in the drawings comprises a single valve mechanism, controlled by a single tracker vent, which may coöperate with all or any of the three above described mechanisms, to negative the effect of opening one or more of the tracker vents T, T^a, T^b. This single valve mechanism is shown by way of illustration at the right of Fig. 1.

A tracker vent R communicates by a duct 80^a with the casing 47 of the valve 46, which valve, in the position assumed for the present, holds the duct 80^a in communication with a duct 80 leading to a diaphragm 85 chamber 82. The latter controls a duplex valve 84 which in its alternative positions, admits atmosphere to a duct 86, or opens said duct into a second duct 88 leading to the high exhaust chest 14. An extension of the duct 86 communicates with each of the three diaphragm chambers 90, 190, 290. Thus when atmosphere is admitted to the duct 86, past the valve 84, the diaphragms of chambers 90, 190, and 290 are distended. In describing the effect of this operation it is convenient to refer to the chamber 190 and associated parts.

As already explained, the valve 158 is held in the position shown by atmosphere admitted to the chamber 162 past the valve 158 and through the ducts 170 and 174. When, however, the diaphragm of chamber 190 is distended, it lifts a disk valve 192 and closes communication between the duct 170 and the duct 174, thereby closing the latter from atmosphere. At the same time the valve 192 opens communication between the duct 174 through the bleeder vent 172 and the chamber 194 which is opened to high exhaust through the duct 160. In this manner the duct 174 is connected with high exhaust which bleeds the atmosphere from the chamber 162 thereby permitting the valve 158 to drop, shutting off atmosphere from the diaphragm chamber 154 and throwing the latter into communication with the chamber 159 and the high exhaust chest 14 through the duct 160. When the diaphragm chamber 154 is thus exhausted, the valve 150 is permitted to drop shutting off atmosphere from the cylinder ducts 41^a and 41 and throwing the duct 41^a into communication with the duct 151 leading to the regulated pressure chest 12. In this manner, merely by opening the tracker vent R, the ducts 41 and 41^a and the cylinder chamber y are closed to atmosphere and opened to regulated pressure.

The operation just described, so far as

concerns the specific illustrative mechanism, depends upon bleeding the diaphragm chamber 162. If the tracker ducts 63 and 63^a be opened through the vent T^a, at the same time 5 that the vent R is opened to initiate the bleeding of diaphragm chamber 162—atmosphere will enter the chamber 162 from the tracker vent more rapidly than it can be exhausted therefrom by the described bleeding 10 through the ducts 170 and 174; therefore the effect of opening the vent R is negatived, and in such circumstances the valve 158 will remain open and atmosphere will continue in the corresponding cylinder 15 chamber.

Also, if the tracker vent T, for instance, be open simultaneously with the tracker vent R, the latter will inaugurate a tendency to bleed the chamber 62 and keep the valve 58 20 closed in the position shown, but the simultaneous opening of the tracker vent T will admit atmosphere to the chamber 62 more rapidly than it can be exhausted by bleeding and therefore the valve 58 will be lifted in 25 spite of the opening of the tracker vent R.

It will be understood, therefore, that in the illustrative apparatus, whether or not the tracker vent R be open, the opening of any vent or vents T, T^a, T^b, will have its 30 normal and usual effect to admit atmosphere to the appropriate chamber or chambers of the cylinder.

On the other hand, if any vent or vents T, T^a, T^b be opened and then closed (atmosphere being thereby admitted to the cylinder) and the vent R be thereafter open, the previous effect of opening the vent or vents T, T^a and T^b will be negatived and regulated pressure will be admitted to the 40 cylinder.

The effect of opening and closing the various tracker vents in the specific mechanism may be readily understood by reference to an illustrative form of perforated music sheet diagrammed in Fig. 3 in which are shown four lines of perforations for governing the expression-controlling tracker vents. This illustrative music sheet may be assumed to be traveling in the direction of 50 the arrow in Fig. 3. The tracker G is shown in dotted lines, the vent T^a being open through a perforation in the sheet as shown. All the other vents are closed. For brevity the perforations in the sheet for 55 operating the motor pneumatics may be disregarded.

When a note sheet and tracker are related, as shown in Fig. 3, the various valve mechanisms occupy exactly the positions illustrated in Fig. 4. If now the music sheet 60 progresses in the direction of the arrow, perforation 101 will presently open the vent R; this will distend the diaphragm of chamber 82; open the duct 86 to atmosphere and 65 admit the latter to diaphragm chamber 190;

lift the valve 192; and throw the diaphragm chamber 162 into communication with the high exhaust chest 14 through the duct 174, past the bleeder 172, through the chamber 194 and duct 160. This permits the valve 158 to drop and thereby the diaphragm chamber 154 is exhausted as described, with the ultimate result that the cylinder ducts 41^a and 41 and cylinder chamber y are closed to atmosphere and opened to regulated pressure. In these circumstances regulated pressure is present in all of the cylinder chambers; and, as previously explained herein, notes will be played with the minimum intensity available in the use of 80 the specific apparatus.

When the music sheet progresses further the perforation 102 opens the vent T and, as will be understood, the ducts 40^a and 40 and cylinder chamber x are opened to atmosphere. Thereafter a perforation 103 and a perforation 104 register respectively and simultaneously with the vents R and T^a. The perforation 103 negatives the previous effect of the perforation 102 and opens 90 the cylinder chamber x to regulated pressure. The perforation 103 is ineffective, however, in respect to perforation 104 which opens the vent T^a and thereby admits atmosphere to the cylinder chamber y. 95

When the next perforations 105, 106 open the vents T, and T^b, atmosphere is admitted to the cylinder chambers x and z. The previous effect of the perforation 104 endures, and therefore by reason of the three perforations 104, 105 and 106, atmosphere is present in all of the cylinder chambers. Next a perforation 107 opens the vent R and simultaneously a perforation 108 opens the vent T^a. The effect of the perforation 107 is to 105 negative the previous effect of both the perforations 105 and 106 and to open the cylinder chambers x and z to regulated pressure. The perforation 107, however, is ineffective in respect to perforation 108 which merely 110 continues the previously established effect of the perforation 104, leaving the cylinder chamber y open to atmosphere.

Next, perforations 109 and 110 reinstate atmosphere in the cylinder chambers x and 115 z and again all the cylinder chambers are open to atmosphere.

Next, a perforation 111 opens the vent R at a time when all the other vents are closed and thereby negatives the effects of all three 120 perforations 108, 109 and 110 with the result that all the cylinder chambers are closed to atmosphere and opened to regulated pressure.

The preceding discussion will suffice to indicate the variety of combinations of 125 perforations whereby atmosphere and regulated pressure may be alternated in one or more of the cylinder chambers with the resultant variations in regulated pressure and in the intensities of notes played thereby.

As will appear to those skilled in the art, the usual note perforations may occur in the music sheet or may be related with the described expression-regulating perforations 5 in any practicable manner. As, for instance, by alining or substantially alining the advance end of a note perforation with one or more expression perforations to establish the regulated pressure in the chest 12 for playing 10 the note with desired intensity. It will appear, moreover, that the expression-regulating perforations may be placed at any practicable distance in advance of perforations for notes desired to be played with the intensities 15 determined by such expression-regulating perforations.

By the arrangement described above, the entire expression mechanism may be operated wholly automatically without any conscious control whatever. A note sheet having suitably associated note and expression perforations may control the absolute intensities of all the notes and at the same time may control the exact relative intensities. 20 Such a wholly automatic mechanism is highly desirable in that it renders practicable the faithful reproduction of a musical performance by an artist through the agency of a note sheet perforated by reference to a suitable record of such performance. It is also desirable, however, especially in a commercial instrument, that such wholly automatic capacity for expression control be combined with some means for 25 exercising a conscious modification of the automatic control, permitting an operator to superpose, as it were, his own interpretation upon that provided for by the arrangement of expression perforations on the note sheet.

Such a wholly automatic mechanism is highly desirable in that it renders practicable the faithful reproduction of a musical performance by an artist through the agency of a note sheet perforated by reference to a suitable record of such performance. It is also desirable, however, especially in a commercial instrument, that such wholly automatic capacity for expression control be combined with some means for exercising a conscious modification of the automatic control, permitting an operator to superpose, as it were, his own interpretation upon that provided for by the arrangement of expression perforations on the note sheet. 30 It is further desirable that means be provided for consciously controlling the expression when no automatic expression-control is utilized as, for instance, when a note sheet is employed which has no expression perforations.

Apparatus for the purposes just suggested is illustrated in the accompanying drawings, by an auxiliary manually operable governing device for the expression mechanism comprising a key 300 arranged when depressed, to exert an upward pull upon the above described piston structure. For illustration, the key 300 is shown with its lower end connected to a cord or wire 302 which 35 passes around pulleys 303, 303 in such manner that downward pressure on the key 300 pulls the wire 302 and thereby lifts, or tends to lift, the piston structure to the stem of which the end of the wire is attached as 40 shown.

The control of the expression through the key 300 is very flexible and when properly exercised may produce a variety of results. For instance, an operator may depress the 45 illustrative key 300 with only sufficient force

to restrict downward movement of the piston structure without wholly preventing it. In other words, if an operator press upon the key 300 yieldingly so as to maintain for example, substantially constant upward pull 70 on the piston structure while permitting downward movement of the structure when the upward pull is overcome, the result may be to increase the absolute intensities of notes played while at the same time leaving 75 the automatic mechanism sufficiently in control to determine wholly or partially the relative intensities of notes. For instance, if the automatic mechanism undisturbed by conscious control would play a note M with 80 an intensity of 10, and a next following note with an intensity of 15, their relative intensities being represented by the difference of 5—depression of the key 300 may increase the absolute intensities of all notes uniformly 85 so that by reason of the conscious control the note M would be played with an intensity of 15 and the note N with an intensity of 20, the automatic mechanism nevertheless maintaining the difference of intensity or relative intensity of 5 between the two notes.

The illustrative modification of the results of automatic control by manipulation of the key 300 or its substitute, which has just been suggested, is merely one of a variety of effects which can be produced by a combination of the automatic and auxiliary control mechanisms which are susceptible of joint use in the production of many and 95 unique effects.

If desired also, the key 300 may be depressed to the lowermost limit of its movement and there held so as to maintain the piston structure at the uppermost limit of its movement leaving the valve ports between the chests 12 and 14 open to the maximum. Under these conditions the automatic control will be superseded and all notes will be 100 played uniformly with the highest intensity 110 available in the use of the specific apparatus. Between this extreme of maximum intensity and the other extreme of minimum intensity when, by unmodified operation of the automatic mechanism regulated pressure is admitted to all the cylinder chambers, there may be a great variety of gradations of intensity, as will readily appear to those skilled in the art.

One advantage which resides in the illustrative construction comprising preferably a direct and substantially unyielding connection between the key 300 and the piston structure, is that an operator depressing the key, exerts in effect a direct pull upon the piston structure and can feel or sense as it were, the effect he is producing to a greater extent than would be likely if the connection between the key or its substitute and the piston structure were readily yielding.

A further capacity for expression control is provided for in the illustrative mechanism, in that the key 300 may constitute means for consciously controlling the expression without conjoint automatic control, as for instance, when a note sheet is employed having no expression perforations. For example, when the valve 46 is set in the position shown in Fig. 1, it will admit and maintain regulated pressure in all of the cylinder chambers opposite the faces x , y and z in the absence of expression perforations to control the tracker vents, T , T^a and T^b . Thus, when a note sheet having no expression perforations is employed, regulated tension, in the specific apparatus, will be present in the cylinder chambers and the resulting pneumatic influence upon the piston 34 and valve 31 will tend to move the entire piston structure downwardly. This downward tendency of the piston structure may be opposed in any desired degree by pressure upon the key 300 so that the operator may consciously vary regulated pressure by merely manipulating the key 300. In the specific apparatus, the spring 37 opposes the downward tendency of the piston structure, and depression of the key 300 augments this opposition by the spring 37 to any degree desired by the operator so that he may cause the instrument to play from pianissimo to fortissimo or vice versa by merely changing the pressure on the key 300. Thus the key 300 and its connections exemplifies means for performing the double function of modifying automatic control when the latter is used, and of controlling expression wholly consciously when the automatic control is not used. At the same time it is possible to use the same ultimate expression controlling means, exemplified by the valve 31 and piston structure, to be governed by the wholly automatic mechanism, or by the latter as consciously modified, or by the means which is wholly consciously operated; in other words the automatic and conscious expression controls may operate the same ultimate means and in substantially the same manner. For example, in the specific apparatus, the wholly automatic control operates through varying the downwardly acting pneumatic pressure opposed by the substantially uniform upward pull of the spring 37; and the wholly manual control operates by varying the upward pull of said spring; while the manual modification of automatic control may involve the varying of both the downward pneumatic pressures and the upward pulls. The mechanical elements and mode of operation by which different intensities are inaugurated and maintained, may remain the same however controlled, the control being exercised merely by varying forces which act upon the said mechanical elements.

Still other effects can be obtained with the illustrative mechanism shown in the drawings. For instance, those skilled in the art are familiar with various attempted expedients for emphasizing or accenting certain selected notes in a composition as for instance theme notes.

It has been proposed heretofore to emphasize such selected notes by introducing to the motor pneumatics, the high exhaust of the feeder bellows for playing notes intended to be accented; and using only a lesser degree of exhaust for other notes which were not intended to be accented. With such an arrangement it has been proposed to employ a single auxiliary tracker vent, which, being opened by a supplemental perforation in the note sheet would throw the feeder bellows into direct communication with the wind chest for the motor pneumatics. Such expedients as these were capable of producing a certain degree of differentiation between theme notes and accompaniment notes, for instance, but the differentiation by such means was objectionably monotonous in its effects in that the exhaust from the feeder bellows caused accented notes to be played with substantially uniform increased intensity, while the other lesser exhaust played the accompaniment notes with substantially uniform minimum intensity; in other words, there were but two intensities available and no delicacy of shading in expression was practicable in such apparatus.

It has also been proposed to afford opportunity for some variation in expression, by rendering the exhaust in the wind chest of the motor pneumatics variable by varying the vigor with which foot-operated feeder bellows were pumped; if pumped rapidly and vigorously, the exhaust would be increased and notes played with a relatively loud intensity, while slow pumping would diminish the degree of exhaust and cause notes to be played more softly. While such an expedient provided for some variations in intensity, the variations were at best extremely crude and no well defined or refined shades of expression were available by such means.

The illustrative apparatus of the drawings embodying the present invention is susceptible of use in connection with a note sheet having but a single line of expression perforations which, in a manner somewhat similar to the control by the note sheet shown in Fig. 3, may control the expression mechanism wholly automatically, or with some modification by an auxiliary device about to be described.

When such a note sheet, having but a single line of supplemental perforations, is employed in the specific mechanism of the drawings, the valve 46 is moved from the position heretofore assumed, into the posi-

tion shown in Figs. 1 and 2, wherein the ducts 40, 41, 163^a, 63^a and 80 are shut off from their previous communication and opened into other ducts as next explained.

5 For the purposes of the specific mechanism shown in the drawings, the single supplemental perforation *p* shown in Fig. 4 is capable of causing a note or notes to be played with any one of three different intensities, disregarding for the present the capacity for still further variation by means of the key 300. These three different intensities which may be inaugurated by the single supplemental perforation are here arrived at 10 by introducing atmosphere or regulated pressure in any desired combination to the cylinder chambers opposite the faces *x* and *y*. The chamber opposite the face *z* always contains regulated pressure in the specific mode 15 of operation about to be described for illustration.

When the valve 46 has been turned to the position shown in Figs. 1 and 2, the cylinder duct 40 communicates with a duct 40^b 25 and the cylinder duct 41 communicates with a duct 41^b. The duct 40^b opens into the chamber of a duplex valve 400 which, in the position shown, admits to the duct 40^b regulated pressure from a chest 402. Said 30 chest 402 is preferably connected in any practicable manner with the main regulated pressure chest 12. When the valve 400 is lifted it cuts off regulated pressure from the duct 40^b and opens communication between 35 the latter and a chest 404, which under some circumstances contains atmosphere as presently described. The duct 41^b likewise opens into the chamber of a duplex valve 406, which opens communication between 40 the duct 41^b and, alternatively, opens the duct 41^b to regulated pressure in the chest 402 and the chest 404.

The valve 400 is controlled by the diaphragm of a chamber 408 which may be 45 vented to atmosphere through a duct 409 by opening a valve 410 which may be controlled by a hand-operated key 420. Each diaphragm chamber 408 and 414 may have suitable bleeding vents (not shown) into 50 the regulated pressure chest 402; by which the diaphragm chambers may be exhausted when the valves 410 and 418 are closed.

The chest 404 is opened alternatively to atmosphere and to regulated pressure in 55 the chest 402 by means of a duplex valve 424, controlled by the diaphragm of a chamber 426, the latter being opened to atmosphere under proper circumstances through a duct 428 through the switch 46 to the tracker 60 duct 163^a leading to the tracker vent T^a, it being assumed that said tracker vent T^a is the one with which will register the single line of supplemental perforations on the assumed note sheet. The chamber 426 may 65 have an appropriate bleeder vent (not

shown) into the chest 402 similar to those described in connection with the chambers 408 and 414.

As illustrated in Fig. 4, the expression-governing tracker vents R, T and T^b may be 70 continuously closed by the note sheet, leaving only the vent T^a to be opened from time to time by the supplemental perforations for the purpose of emphasizing selected notes.

With this arrangement, and with the 75 auxiliary mechanism just described, the intensity of played notes may be controlled and varied as follows:

So long as the tracker vent T^a is closed, shutting off atmosphere from the ducts 163^a 80 and 428, the chamber 426 will be bled permitting the valve 424 to rest in the position shown in Fig. 1, in which it opens the chest 404 to regulated pressure from the chest 402. In this situation, regulated pressure 85 is on both sides of the two duplex valves 400 and 406; consequently, manipulation of the keys 411 and 420 can have no effect to admit anything but regulated pressure to the ducts 40^b and 41^b and through them and 90 the ducts 40 and 41 to the cylinder chambers. Accordingly, so long as the tracker vent T^a remains closed, regulated pressure will be 95 present in the cylinder chambers opposite the piston faces *x* and *y*, and also as above suggested, opposite the piston face *z*.

If, however, a perforation in a note sheet, opens the tracker vent T^a atmosphere will be admitted to the chamber 426, the diaphragm of which will lift the valve 424, admitting 100 atmosphere to the chest 404. This of itself has no immediate effect upon pneumatic conditions in the expression cylinder; but if the key 411 for instance, be depressed, the chamber 408 will be vented to atmosphere, lifting 105 the valve 400 and opening the duct 40^b to atmosphere through the chest 404, and past the valve 406. This admits atmosphere through the duct 40 to the cylinder chamber opposite the piston face *x*. Likewise, if the 110 key 420 be depressed while the valve 424 is open to atmosphere, atmosphere is admitted past the valve 406 to the duct 41^b, and through the duct 41 to the cylinder chamber opposite the piston face *y*.

Thus, the opening of the tracker vent T^a by a supplemental perforation in a note sheet may effect no change (if neither key 411 or 115 420 be depressed) in the previously prevailing regulated pressure; or, if the key 420 be 120 depressed, it may admit atmosphere opposite the piston face *y* to cause a selected note to be played more loudly; or if the key 411 be depressed it may admit atmosphere opposite the piston face *x* to cause notes to be played 125 still more loudly; or if both the keys 411 and 420 be depressed they may admit atmosphere opposite both faces *x* and *y*, to cause notes to be played with maximum loudness (neglecting for the time being, possible modification 130

by the key 300). It appears, therefore, that only a single supplemental perforation in the note sheet may, at the will of the operator, in the specific mechanism, cause notes to be played with any one of several intensities. Whereas, in the prior art devices discussed above, a supplemental perforation could have but the single effect of increasing intensity to a substantially fixed and uniform maximum, in the present illustrative mechanism such single supplemental perforation may be utilized to institute any selected one of a plurality of available intensities.

The described manner of using a single row of supplemental perforations presents features of substantial advantage; for instance, the usual fixed relation between supplemental perforations and note perforations in a sheet may well determine, more accurately than would be practicable with manual control by the average operator, the moment when the expression mechanism is brought into play to affect the intensity of the selected note or notes. In other words, the fixed relations between the supplemental and note perforations of the sheet, prearranged by the experts who lay out the sheets, may determine the exact moment when the expression mechanism initiates its intended operation. At the same time, the operator may, at will, predetermine which one of several intensities shall be given to a note or notes when the supplemental perforation starts the operation of the expression mechanism.

Added to the described flexibility of expression-control, in connection with a note sheet for but a single line of supplemental perforations—is the still further capacity for modification by means of the key 300 or its substitute having a connection with the expression mechanism, such, for example, as that described with reference to the piston structure.

45 For instance, if both the keys 411 and 420 be depressed (assuming the tracker vent T^a to be open) atmosphere will be admitted to the cylinder opposite the piston faces x and y ; if at the same time the key 300 be depressed, the effect may be as though atmosphere had been admitted also opposite the piston face z , or may be intermediate that effect and the effect of atmosphere opposite the faces x and y alone.

55 It will be noted that the tracker duct 80^a is cut off from the duct 80 when the valve 46 is thrown to position to switch in the ducts 40^b and 41^b. Therefore, the tracker vent R is in any case idle, and it is immaterial whether or not it is maintained closed by the note sheet. For the purposes of the specific apparatus, however, it is preferred that the duct 80 be continuously open to atmosphere, and, accordingly, when the valve 65 46 occupies the position shown in Figs. 1

and 2, the duct 80 communicates with an open-ended duct 450. With this arrangement the diaphragm of chamber 82 is continuously distended and atmosphere is admitted continuously to the duct 86. The effect of this upon the valves 92 and 192 is immaterial, since the mechanisms associated with said respective valves are temporarily inoperative, their controlling ducts 63 and 163 and also their ducts 40^a and 41^a running to blind ends in the valve 46, as shown in Fig. 2. The continuous presence of atmosphere in the duct 86, serves, however, to hold the diaphragm of chamber 290 continuously distended, thereby bleeding the chamber 262 and ultimately causing the valve 258 to close downwardly, and maintaining regulated tension in the cylinder chamber opposite the face z . Thus it will be seen that to switch the duct 80 into communication with the open-ended duct 450 serves to maintain regulated pressure always opposite the piston face z ; this pertains of course only to the specific apparatus of the drawing, it being evident to those skilled in the art that the duct 42, if desired, could be switched from one control to another in a manner similar to that described in connection with the ducts 40 and 41, thereby permitting variations in the pneumatic condition in the cylinder opposite the face z and extending the scope of expression variations available in the described apparatus.

Preferably, the duct 63^a from the tracker vent T communicates with a blind end 452 when the valve 46 has the position shown in Figs. 1 and 2. Thus the tracker vent T is idle and it is immaterial whether or not it is covered by the note sheet.

In the specific mechanism the duct 263 leading from the tracker vent T^b leads directly to its diaphragm chamber 262, and for this reason it is preferable that the tracker vent T^b be maintained closed by the note sheet when only a single line of perforations is being used.

It is not indispensable that a note sheet with only a single line of supplemental perforations be used with the described apparatus when the switch 46 occupies the position shown in Figs. 1 and 2; on the contrary it would be possible to use under those circumstances the note sheet shown in Fig. 3. In such use the supplemental perforations registering with the tracker vent R would have no effect since the duct 80^a of the vent R runs to an open tube at the switch 46. Likewise, the perforations registering with the vent T would be idle since the duct 63^a, running to said vent, also runs to a blind end 452. The perforations to register with the vent T^a would have the effects of those shown in the note sheet of Fig. 4 and hereinbefore described. The perforations registering with the tracker vent T^b would each

admit atmosphere to the cylinder opposite the piston face 2; and atmosphere would be exhausted from said chamber, when the vent T was again closed, by the described continuous venting of the duct 80 to atmosphere, maintaining atmosphere always in the duct 86.

The above described apparatus suffices to illustrate the variety of forms and organizations in which the various features of this invention may be embodied. While it is not indispensable that all the features of the invention be used conjointly, it is desirable, as will appear to those skilled in the art, that an instrument intended for general commercial exploitation provide a widely flexible opportunity for expression-control such as that available in the specific apparatus above described. For instance, the specific apparatus comprises a plurality of different governing mechanisms for the expression-controlling means exemplified by the valve 31. One such governing means comprises the valve mechanisms pertaining to the valves 50, 150 and 250 which may be controlled wholly automatically from the tracker. Another such governing means comprises the valves 400, 406 and 424 with their associated devices by which the time relation between the sounding of notes and the operation of the expression-controlling means may be predetermined automatically while different degrees of intensity of the notes may be predetermined, if desired, by manual control. The correlation of two such governing means in the same instrument gives the latter a wide scope of use with perforated note sheets, or the like, of different constructions and arrangements and at the same time permits the operator to contribute at will his own interpretation or else to leave the instrument to its completely automatic expression-control.

In the specific illustrative organization hereinbefore described, it will be noted that the governing means comprising the valve mechanisms for the valves 50, 150 and 250, has the capacity to predetermine and initiate various levels or grades of intensity each of which, when once established, endures until deliberately replaced by another. For instance, when perforations such as 103 and 104 of Fig. 3 once establish a certain regulated pressure in the chest 12, that regulated pressure will continue and will play notes with uniform intensity until regulated pressure is intentionally varied by succeeding perforations. The second governing means above mentioned, comprising the valves 400, 406 and 424, has, for the purposes of the specific illustrative apparatus, a capacity quite different from that just explained; that is to say the governing means comprising the valves 400, 406 and 424 is arranged to accent or emphasize selected notes or

groups of notes with a merely momentary effect followed by a substantially immediate resumption of the previously prevailing intensity. In other words, in the use of the governing means comprising the valves 400, 406 and 424, there may be one substantially uniform level of intensity at which most of a composition is played, the governing means serving from time to time momentarily to accent or emphasize the selected note or notes, after which the normal uniform level of intensity is substantially immediately resumed. In short, one of the two governing means predetermines different enduring levels or grades of intensity; while the other governing means may predetermine merely momentary accents. The presence of two such different means for governing expression, in the same instrument, contributes obviously a wide and desirable scope of expression-control.

In addition to the two governing devices just pointed out, which in the specific instrument are alternatively operative—there may be a third governing means such as that exemplified by the key 300 and its connections with the illustrative piston structure. By means of this third governing means the operator is afforded at all times an opportunity to vary the automatic or partly automatic behavior of the apparatus to suit his own fancy in respect to expression.

As has been stated already, it is not indispensable that all the features of the invention be used conjointly since they may be used to advantage separately. Furthermore, it is to be understood that the invention is by no means limited to the specific constructions, organizations and modes of operation hereinbefore specifically described for purposes of illustration, since, as will be evident to those skilled in the art, the features of the invention may be variously embodied and practised within the scope of the subjoined claims.

Claims:

1. A tone-governing apparatus for musical instruments comprising, in combination, a tracker; a container for regulated pressure; a high exhaust chamber; a valve to govern communication between regulated pressure and high exhaust; expression-controlling means to govern said valve, comprising pneumatically-governed piston means; automatic tracker-controlled governing means for the expression-controlling means, comprising a plurality of valve mechanisms to vary pneumatic action upon said piston means; additional tracker-controlled governing means for the expression-controlling means, comprising a plurality of manually-operable means to vary pneumatic action upon said piston means; a switch-valve-mechanism for connecting said

respective governing means alternatively with the expression-controlling means; and a third governing means for the expression-controlling means, comprising manually operable means to modify the effects of the other governing means on the expression-controlling means.

2. A tone-governing apparatus for musical instruments comprising, in combination, 10 a tracker; a container for regulated pressure; a high exhaust chamber; a valve to govern communication between regulated pressure and high exhaust; pneumatically-operated expression-controlling means to 15 govern said valve; automatic tracker-controlled governing means for the expression-controlling means, to vary pneumatic action upon the latter; additional tracker-controlled governing means, comprising a plurality of manually-operable means, to vary pneumatic action upon the expression-controlling means; a switch-valve-mechanism for connecting said respective governing means alternatively with the expression-controlling means; and a third governing 20 means for the expression-controlling means, comprising manually operable means to modify the effects of the other governing means on the expression-controlling means.

3. A tone-governing apparatus for musical instruments comprising, in combination, a tracker; a container for regulated pressure; a high exhaust chamber; a valve to govern communication between regulated pressure and high exhaust; pneumatically-operated expression-controlling means to 30 govern said valve; automatic tracker-controlled governing means for the expression-controlling means; additional tracker-controlled governing means for the expression-controlling means, comprising a plurality of manually-operable means; and a switch-valve-mechanism for connecting said respective governing means alternatively with the expression-controlling means.

4. A tone-governing apparatus for musical instruments comprising, in combination, a tracker; a container for regulated pressure; a high exhaust chamber; a valve to 40 govern communication between regulated pressure and high exhaust; expression-controlling means to govern said valve; automatic tracker-controlled governing means for the expression-controlling means; additional tracker-controlled governing means for the expression-controlling means; and a switch-valve-mechanism for connecting said respective governing means alternatively with the expression-controlling means.

5. A tone governing apparatus for musical instruments comprising, in combination, a container for regulated pressure; a high exhaust chamber; a valve to govern communication between regulated pressure and high exhaust; expression-controlling means

to govern said valve; governing means for the expression controlling means; a controller for the latter means; additional governing means intermediate said controller and the expression-controlling means for 70 modifying the control by the former of the latter; and means for connecting said respective governing means alternatively with the expression controlling means.

6. A tone-governing apparatus for musical instruments comprising, in combination, 75 a container for regulated pressure; a high exhaust chamber; a valve to govern communication between regulated pressure and high exhaust; expression-controlling means 80 to govern said valve; automatic governing means for the expression-controlling means; additional governing means for the expression-controlling means; a switch-valve-mechanism for connecting said respective 85 governing means alternatively with the expression-controlling means; and a third governing means for the expression-controlling means, for modifying the effects of the other governing means on the expression-control- 90 ling means.

7. A tone-governing apparatus for musical instruments comprising, in combination, means to provide pneumatic pressure; expression-controlling means to vary said 95 pneumatic pressure for sounding tones with different intensities; a plurality of governing means; means rendering said governing means alternatively operative for the expression-controlling means; and an additional 100 governing means for the expression-controlling means, for modifying the effects of the other governing means on the expression-controlling means.

8. A tone-governing apparatus for musical instruments comprising, in combination, 105 means to provide pneumatic pressure; expression-controlling means to vary said pneumatic pressure for sounding tones with different intensities; a plurality of governing 110 means; means rendering said governing means alternatively operative for the expression-controlling means; and additional governing means coöperable with each of said plurality of governing means.

9. A tone-governing apparatus for musical instruments comprising, in combination, means to provide pneumatic pressure; expression-controlling means to vary said 115 pneumatic pressure for sounding tones with different intensities; a plurality of governing means for the expression-controlling means; means rendering said governing means alternatively operative and additional manually-controlled governing means 120 coöperable with each of said plurality of governing means.

10. A tone-governing apparatus for musical instruments comprising, in combination, 125 a tracker; expression-controlling means; 130

governing means for the expression-controlling means, governed by a plurality of tracker vents; and alternatively-operative governing means for the expression-controlling means, governed by a single tracker vent.

11. A tone-governing apparatus for musical instruments comprising, in combination, a tracker; expression-controlling means; governing means for the expression-controlling means, governed by a plurality of tracker vents; and alternatively-operative manually-operable governing means for the expression-controlling means, governed by 15 a single tracker vent.

12. A tone-governing apparatus for musical instruments comprising, in combination, expression-controlling means; automatic governing means for the expression-controlling means; alternatively-operative partly automatic and partly manually-controlled governing means for the expression-controlling means; a tracker connected to said automatic governing means, and means rendering said several governing means alternatively operative.

13. A tone governing apparatus for musical instruments comprising, in combination, tone sounding means; means to control the sequence of sounding of respective tones, including a note sheet having a single perforation for each of a plurality of tones to be sounded; means for varying the effective power of said tone sounding means; expression governing means for controlling said power variation, including means automatically operable from the note sheet; and further means controllable by the operator to determine the extent of said power variation caused by said automatically operable expression governing means.

14. A tone governing apparatus for musical instruments comprising, in combination, tone sounding means; means to control the sequence of sounding of respective tones, including a note sheet having a single perforation for each of a plurality of tones to be sounded; means for varying the effective power of said tone sounding means; expression governing means for controlling said power variation, including means for automatically determining the time of operation thereof; and variable means to determine the ultimate effect of the operation of said expression governing means at such time.

15. A tone governing apparatus for musical instruments comprising, in combination, tone sounding means; means to control the sequence of sounding of respective tones, 60 including a note sheet having a single perforation for each of a plurality of tones to be sounded; means for varying the effective power of said tone sounding means; expression governing means for controlling said power variation, including means for auto-

matically determining the time of operation thereof; and manually controllable means to determine the ultimate effect of the operation of said expression governing means at such time.

16. A tone governing apparatus for musical instruments comprising, in combination, tone sounding means; means to control the sequence of sounding of respective tones, including a note sheet having a single perforation for each of a plurality of tones to be sounded; means for varying the effective power of said tone sounding means; expression governing means for controlling said power variation, including means for automatically determining the time of operation thereof; and means controllable by the operator for varying the ultimate effect of the operation of said governing means.

17. A tone-governing apparatus for musical instruments comprising, in combination, expression-controlling means; automatic governing means therefor to set up a plurality of different grades of intensities; and alternative governing means for the expression-controlling means for automatically setting up momentary accents for selected notes.

18. A tone-governing apparatus for musical instruments comprising, in combination, expression-controlling means; governing means therefor to set up a plurality of different grades of intensities; and alternative governing means for automatically setting up momentary accents.

19. A tone-governing apparatus for musical instruments comprising, in combination, tone-sounding means governed by a controlling agent; mechanism for causing enduring variations in said controlling agent for sounding tones at different levels of intensity; and alternative automatically operable means for momentarily varying said controlling agent for accenting tones.

20. A tone-governing apparatus for musical instruments comprising, in combination, expression-controlling means, a tracker having a plurality of expression-vents therein; automatic mechanism governed by said plurality of vents for varying the expression mechanism to produce different levels of intensity; and alternatively-operative means governed by one of said plurality of vents to vary said expression-controlling means.

21. A tone-governing apparatus for musical instruments comprising, in combination, expression-controlling means, a tracker having a plurality of expression-vents; and a plurality of governing means for the expression-controlling means, controlled respectively by one and all said plurality of tracker vents.

22. In a musical instrument, the combination of expression-controlling means; means

for governing the latter by opposed forces; automatic means to vary those said forces acting in one direction; and means controllable by the operator for varying the summation of said forces acting in the opposite direction.

23. A tone governing apparatus for musical instruments comprising, in combination, a container for regulated pressure; a high exhaust chamber; a valve to govern communication between regulated pressure and high exhaust; expression-controlling means to govern said valve; governing means for the expression-controlling means; a controller for the latter means; additional

governing means intermediate said controller and the expression-controlling means for modifying the control by the former of the latter; and switch-valve-mechanism for connecting said respective governing means alternatively with the expression-controlling means. 20

In testimony whereof, I have signed my name to this specification in the presence of two subscribing witnesses.

CHARLES F. STODDARD.
